(57) **CLAIM**

The ornamental design for a bait holder, as shown and described.

DESCRIPTION

FIG. 1 is a perspective view of the bait holder of the present invention;

FIG. 2 is a left side view of the bait holder shown in FIG. 1;

FIG. 3 is a right side view of the bait holder shown in FIG. 1;

FIG. 4 is top view of the bait holder shown in FIG. 1;

FIG. 5 is bottom view of the bait holder shown in FIG. 1;

FIG. 6 is front view of the bait holder shown in FIG. 1;

FIG. 7 is rear view of the bait holder shown in FIG. 1; and,

FIG. 8 is a perspective view of the bait holder in an open position.

The broken line showing of environment in the drawings is for illustrative purposes only and forms no part of the claimed design.
